GEORGE NYMANNING, OF LOS ANGELES, CALIFORNIA.

DRILLING-BIT.

1,351,262.

Specification of Letters Patent. Patented Aug. 31, 1920.

Application filed January 9, 1920. Serial No. 350,464.

To all whom it may concern:

Be it known that I, GEORGE NYMANNING, a citizen of the United States, residing at Los Angeles, in the county of Los Angeles 5 and State of California, have invented new and useful Improvements in Drilling-Bits, of which the following is a specification.

This invention relates to rotary drilling bits and has for its object to provide an improved bit to facilitate cutting operations, and further to provide a bit that may be readily sharpened by the usual facilities convenient at a well instead of having to transport the bit to a remote repair shop or 10 plant; and further to provide a bit of this type of integral construction, thus avoiding the possibility of losing separate parts and causing serious trouble as occurs when the tool is made in sections. Another object of 15 the invention is to provide a bit of the fish-tail character that is economical in cost of construction and in the quantity of material utilized. The invention consists of the construction and details, an embodiment of 20 which is illustrated in the accompanying drawing and described and claimed herein.

Figure 1 is a side elevation of the bit.

Fig. 2 is an edge elevation of the bit looking toward the right edge of Fig. 1.

Fig. 3 is a transverse section on line 3—3 of Fig. 1.

The bit is designed to be readily forged out of a single piece of material of suitable dimensions according to the size of the bit 35 to be produced, and is preferably so constructed and shaped that it may be readily sharpened after a period of use on an anvil such as may commonly be found around a well structure. The tool comprises an upper body portion 2 termed the butt, more or less cylindrical in form and having a transverse shoulder or end 3 from which projects the usual threaded shank 4 to receive a driving rod operative by any suitable rotary 40 drill head arranged at the well works. The body of the tool, while it is given the general outline of the wellknown form of fish-tail tool, is in the present case bifurcated to form substantially duplicate downwardly 45 extending blades 5 and 6 diverging from the crotch 7 of the butt 2 outwardly toward their lower ends, as clearly shown in Fig. 2. The blades, while they decrease in thickness from their upper portions toward their 55 lower ends, increase in width so that their side faces near the ends are wider than the

upper portions of the side faces. Thus by the width of the blades 5 and 6 and by their offsetting with respect to the longitudinal axis of the bit as clearly shown in Fig. 3, 60 the diameter of the hole being drilled is determined.

The lower cutting edges 8—8 are each inclined inwardly and upwardly from the extremities 9 of the blades to form an obtuse 65 angle relatively between the edges 8—8, as shown in Fig. 1, and thus to provide for the cutting of a substantially conical shaped core at the bottom of the hole during the drilling in the manner common to the fish-tail bit. The lower portions of the blades 5 and 6 may be of concavo convex form as shown in Fig. 3 so as to produce a cutting effect at its points 10—10 Fig. 3, after the manner of a plowshare. 70

These cutting points may be deflected inwardly to form lips 11 shown in Fig. 2.

A further improvement in tools of this general type is secured by terminating the water holes 12 leading in through the 80 threaded shank 4 at the top of the space formed between the upper ends of the blades 5—6 so that the water supplied during drilling is forced directly against the cutting blades and the washing of the hole is accelerated. 85

Various changes may be made without departing from the spirit of my invention, as claimed. 90

I claim.

1. A fish-tail, rotary cutting bit comprising a butt or head portion with downwardly extending laterally spaced rigid cutting blades, the blades relatively offset to each other and a threaded shank extending upwardly from said butt. 95

2. A fish-tail, rotary cutting bit comprising a butt or head portion with downwardly extending laterally spaced rigid cutting blades, the blades relatively offset to each other; the lower edges of the blades inclining upwardly and inwardly to form an obtuse angle relatively. 100

3. A fish-tail, rotary cutting bit comprising a butt or head portion with downwardly extending laterally spaced rigid cutting blades, the blades relatively offset to each other; the lower ends of the blades being of concavo convex cross section, the lower edges of the blades inclining upwardly and inwardly to form an obtuse angle relatively. 110

4. A fish-tail, rotary cutting bit compris-

ing a butt or head portion with downwardly extending laterally spaced rigid cutting blades, the blades relatively offset to each other; the butt of the bit being provided 5 with water holes terminating between the upper spaced ends of the blades.

5. A fish-tail rotary cutting bit comprising a butt, blades extending downwardly from said butt and spaced laterally and off-

set relatively to each other, a threaded shank 10 extending upwardly from said butt, said shank and said butt being provided with water holes extending therethrough and terminating at their lower ends between the upper spaced ends of said blades.

In testimony whereof I have signed my name to this specification.

GEO. NYMANNING.
